UNITED STATES PATENT OFFICE.

JOSIAH W. THOMPSON, OF MILTON, ASSIGNOR OF ONE-HALF TO SAMUEL B. LOCKLIN, OF BOSTON, MASSACHUSETTS.

WINDOW-SCREEN.

SPECIFICATION forming part of Letters Patent No. 290,496, dated December 18, 1883.

Application filed June 18, 1883. (No model.)

To all whom it may concern:

Be it known that I, JOSIAH W. THOMPSON, of Milton, county of Norfolk, State of Massachusetts, have invented an Improvement in a Window-Screen, of which the following description, in connection with the accompanying drawings, is a specification, like letters on the drawings representing like parts.

My invention relates to a window-screen of that class in which a flexible screen is mounted on a roller after the manner of the usual window-shades, and is connected with the sash and drawn out or unrolled in proportion as the sash is raised or opened, to thus cover the space opened by the sash and prevent the ingress of flies and mosquitoes or other insects.

In the accompanying drawings, Figure 1 is a front elevation, and Fig. 2 a vertical longitudinal section, of a window provided with a screen embodying this invention.

The window-frame *a* contains the usual sliding sashes, *b* *c*, which may be balanced by weights *d* in the usual manner. When the sash is to be used with the lower sash, it is mounted on a winding roller, *e*, near the bottom of the window-frame, the said roller being operated by a spring to keep the screen *f*, which consists of any suitable flexible fabric or webbing wound upon it when not in use, and to hold it drawn tightly in place when in use. The said screen is led from the roller *e* over a guide-roller, *h*, located close to the sill or lower portion of the window-frame, and is connected with a cross-piece, *i*, adapted to slide in guides *k* at the sides of the window-frame, the said guides also holding the edges of the screen when the said cross-piece *i* is raised. The cross-piece *i* is provided with T-shaped notches *m* to receive the flattened shanks of buttons *n*, which, when turned into vertical position, will allow the said shanks to pass freely through the said notches, so that the sash may be raised without carrying the screen with it when desired to have a free opening through the window. When, however, the buttons are turned to the horizontal position, as shown, the shanks of the buttons engage the cross-piece *i*, fastening it to the lower rail of the sash and caus-

ing it to move therewith, so that as the sash is raised or the window is opened the screen is drawn out to cover the opening. The guide-roller *h* never has but a single thickness of the screen over it, and consequently may be placed to keep the said screen close to the sill, so that no space is afforded for the entrance of insects, its effective part thus always having the same position with relation to the frame, whether a greater or less amount is unwound from the window *e*; but when the screen is unwound directly from the roller *e* without the guide-roller *h*, as has usually been practiced in window-screens of similar character, a space will be left below the said roller by the unwinding of the different layers of the screen material from it.

The roller *e* may, if desired, be inclosed by a guard, *o*, and a screen may, if desired, be employed in a similar manner in connection with the upper sash, as shown in dotted lines Fig. 2, it also having a guide-roller to keep it close to the window-frame.

The guide *k* is shown as a groove in the usual removable strip at the side of the window by which the sash is held in the frame, and the lower portion, *p*, of the said strip, containing the bearings for the rollers *e* and *h*, may, if desired, be made separate from the remainder of the strip, as shown, so as to enable the entire screen to be removed, if desired, the said portions *p* being normally held in place by suitable fastenings, shown as hooks *r*.

A screen of this construction of fine material may be used in railway-cars to admit air and exclude the cinders, and it is obvious that the screen proper may be made of any kind of material suitable for the use to which it is to be put. The screen may, if desired, be raised or drawn out without raising the sash for the purpose of partly obstructing the view through the window. When the screen is used with the upper sash, the guide *k* may be made in the parting-bead for the sashes.

I claim—

1. The combination, with a window-screen substantially such as described, of the strip provided with the notches *m*, to receive turn-

buttons *n*, whereby the screen may be easily and quickly detached from the window, as set forth.

2. The window-frame having a guiding-groove, *k*, in the sash-holding strip, combined with the screen, its winding and guiding rollers, and the removable bearing-pieces *p* therefor, substantially as described.

In testimony whereof I have signed my name to this specification in the presence of two subscribing witnesses.

JOSIAH W. THOMPSON.
